UNITED STATES PATENT OFFICE

WILLIAM R. TUTTLE AND CHARLES W. STICKEL, OF ROCHESTER, NEW YORK, ASSIGNORS
TO THE KURLASH COMPANY, INC., OF ROCHESTER, NEW YORK, A CORPORATION OF
NEW YORK

COSMETIC COMPACT

Application filed March 14, 1932. Serial No. 598,742.

This invention relates to improvements in cosmetic compacts and more particularly to a compact which is provided with moistening elements.

5 The invention specifically is an improvement over the invention embodied in the copending United States application No. 586,013 filed January 11, 1932, in the names of the same applicants herein.

10 A broad object of the present invention is provision of a compact provided with a new and novel casing for a moistening element.

15 Another object of the invention is provision of means for the withdrawal of the said casing from the compact, the said withdrawal being necessitated whenever it is desired to saturate the said moistening element with water.

20 Another object of the invention is provision of a compact having a construction conducive to the removable structure of the aforesaid moistening element casing.

25 These objects and other incidental features of the invention will be brought out in the following disclosure and in the accompanying drawing forming a part hereof and wherein like reference characters represent corresponding parts throughout the several views.

30 Moreover, the general structure of the compact cooperating with the subject matter of the present invention will be set forth merely as a reiteration of the specification embodied in the copending application serially numbered 586,013, as above said.

35 Referring to the drawing, Figure 1 is a view in perspective showing a preferred form of a compact in open and operative position, casing 7, the subject matter of this invention, being shown in perspective and in cooperation therewith;

Figure 2 is a plan view of the lower portion of the compact shown in Figure 1;

40 Figure 3 is a longitudinal cross-sectional view through the line 3—3 of Figure 2.

45 In accordance with the invention, the compact comprises an upper portion 1 pivotally connected at 16 to the lower portion 2, the side walls of the said portions being preferably perpendicular to the upper and lower faces of the said two portions. 1 and 2 com-

prise the compact case proper, the side walls of the same offering sufficient height for the reception and enclosure of the elements hereinafter to be described. 17 represents a spring catch which is the usual mechanism employed in the opening and closing of compact cases of the variety shown in Figure 1 of the accompanying drawing, it being deemed unnecessary to show the cooperating notch with spring 17 on the front wall of the upper portion 1 of the compact case. 3 represents a flat mirror which is affixed in any known fashion to the inner face of upper portion 1 and is used for the usual purposes.

55 The compact case thus far described is preferably rectangular in shape, it being understood that the shape of the compact case is not of the essence of the invention. The external portions of the compact case may be enameled, engraved, or otherwise decorated for the usual aesthetic reasons.

60 4 represents an intermediate base plate engaging the side walls of lower portion 2 at the peripheral edges thereof, as shown in Figure 3. Intermediate base plate 4 consequently is in spaced relation with respect to the upper face of lower portion 2 of the compact case. 5 represents a casing for any cosmetic cake material, such as mascara, which said material requires for application a moistened 65 brush. Casing 5 is adapted to rest on the upper face of lower portion 2 by penetrating intermediate base plate 4 through an opening 70 conforming to the peripheral shape of casing 5.

75 Casing 5 preferably comprises a continuous side wall, the shape of the said casing being of any desired form but preferably rectangular. The upper edge of casing 5 is turned in at any desired curvature or flange but, as shown in Figure 1, constitutes merely a continuous and inward extension of the upper edge. 6 represents a cake of mascara, which is encased in casing 5, and which is removable when worn down for replenishing 80 purposes.

85 90 95 100 7. The subject matter of the invention herein, represents a casing or holder for a moistening element, such as sponge 9, and comprises preferably a rectangular body with an upper facing having an opening 8 and con-

tinuous side walls, as shown in Figure 1. The opening 8 is preferably in the form of a diagonal slot and permits exposure of the upper face of sponge 9. Holder 7 is supported through an opening in intermediate base plate 4 conforming to the desired peripheral shape of holder 7. The said holder or casing 7 is held in position by frictional engagement with the turned-down portions of the periphery of intermediate base plate 4 at the above said opening. It is seen by a reference to Figure 3 that casing 7 is permitted to engage with the opening in intermediate base plate 4 to the extent of penetrating the upper face of lower portion 2 through the agency of lower cup portion 25, as will hereinafter be set forth.

25 represents a cup portion adapted to hold sponge 9. Said cup portion 25 with sponge 9 attached thereto is constructed to fit into the interior from the bottom of casing 7 in a manner such that the upper face of sponge 9 becomes exposed through the diagonal slot 8 of casing 7. Intermediate base plate 4 is provided with a narrow slot 26 at a distance from the receptacle for casing 7, the said slot 26 engaging levers 22 and 23 by means of an intermediate bearing portion 24. Lever 23 is adapted to rest on the surface of the upper face of lower portion 2 within the space allotted for the bottom portion of casing 7, as best shown by a reference to Figure 3.

Lever 22 projects from intermediate base plate 4 from bearing 24. It is seen that by bearing pressure on the upper face of lever 22, lever 23 is caused to ascend and thus raise therewith the whole of casing 7, it being remembered that the amount of pressure necessary to be borne on lever 22 depending upon the frictional engagement between the side walls of casing 7 and the turned-in portions of intermediate base plate 4. Levers 22 and 23 may be made of one piece of metal offset intermediate the ends of the levers and thus afford the intermediate or fulcruming portion 24. It is thus seen that levers 22 and 23 operate to furnish an ejector for casing 7 whenever it is desired to saturate sponge 9 contained therein. We wish it understood at this point that the invention of this application resides in the structure of a casing for a moistening element together with an ejector therefor in cooperation with the rest of the description herein contained.

Casing 5 and holder 7 are arranged preferably in longitudinal alignment and adjacent to the rear and side walls of lower portion 2 for space conservation, all as preferably represented in Figure 1 of the accompanying drawing.

69 10 represents the handle of the application brush comprising head 11 and bristles 12. 13 is a casing for the upper portion of the application brush, the said casing comprising a front wall 14, an end and outer wall 20 and upper and lower walls 21. 15 is a tongue

member attached to the lower edge of end and outer wall 20 and penetrates intermediate base plate 4 in a transverse slit, said tongue member being adapted to give casing 13 vertical movement so that handle 10 of the 70 application brush is normally at an acute angle with respect to intermediate base plate 4. The purpose of tongue member 15 in association with casing 13 is toward offering easy 75 insertion and removal of the application brush, as becomes apparent from a reference to Figure 1. Casing 13 is preferably positioned adjacent to the front and outer walls 80 of lower portion 2 for space conservation. The views herein omit 15.

The compact itself may be made of any 85 metallic or nonmetallic material, the same being true for casing 5, casing or holder 7, casing 13 and intermediate base plate 4; but in the present embodiment of the invention 90 metal has been chosen. Respecting the relative placement of the several parts of the structure, the present embodiment is aimed toward compactness and facility of use; and for such reason elements 5, 7 and 13 have 95 been positioned, as represented in the accompanying drawing.

The present invention proper comprises in 100 cooperation with a compact case of the type described an easily removable and insertable 95 casing for a moistening element. To those versed in the art, it is known that the application of mascara for best results requires a brush that necessarily must be moistened; the 105 source for such moistening being in casing 7 100 of the compact case described.

The present structure of a compact case 110 has an advantage over others in that the same is provided with a moistener which eliminates 105 the necessity and the need for proximity to a source of water supply where the cosmetic material, such as mascara, requires water for 115 its application. The user of the present structure need but saturate sponge 9 each morning so that there will be at least one day's 110 supply of moisture for the application brush in conjunction with the mascara or other material requiring the use of water for its 120 application.

I wish it understood that minor changes 115 and variations in the structure, location, size, and shape of the various parts may be resorted to without departing from the spirit 120 of the invention nor departing from the scope of the appended claims.

We claim:

1. In combination with a compact case having an intermediate base plate as described, a casing for a moistening element or sponge adapted to engage with an opening in the said intermediate base plate, and means to raise the said casing.

2. In combination with a compact case having an intermediate base plate as described, a casing for a moistening element or sponge

and having an opening in the upper face thereof, the said casing resting on the bottom of the compact case and fixed in place by an opening in the intermediate base plate,
5 and means to raise the said casing.

3. In combination with a compact case having an intermediate base plate as described, a casing for a moistening element or sponge and having an opening in the upper face
10 thereof, the said casing resting on the bottom of the compact case and fixed in place by an opening in the intermediate base plate, an external actuating lever and an actuated lever situated beneath the said casing to raise
15 the same for removal purposes.

4. In combination with a compact case having an intermediate base plate as described, a casing for a moistening element or sponge and having an opening in the upper face
20 thereof, the said casing resting on the bottom of the compact case and fixed in place by an opening in the intermediate base plate, and levers adapted to raise the said casing for removal purposes.

25 Signed at Rochester, in the county of Monroe and State of New York, this 11th day of March, 1932, A. D.

WILLIAM R. TUTTLE.
CHARLES W. STICKEL.
